TELEPHONE RECORDER-REPEATER
SYSTEM

Isadore Lawrence Lesavoy, Allentown, Pa.

Application March 15, 1941, Serial No. 383,505

11 Claims. (Cl. 179—6)

This invention relates to a telephone recorder-repeater system wherein upon dialing a subscriber's number, a caller will be automatically connected with mechanism which, at his will, can be caused to record a message or to repeat a message previously recorded. Thus, a subscriber can leave a message which will be repeated to a subsequent caller, or a caller can leave a message which the subscriber can subsequently obtain.

Briefly, the invention contemplates the equivalent of a standard central office system with incoming trunks under the control of a central office operator. The final connectors, however, instead of terminating in subscriber's telephones, are capable each of being connected to a recording-repeating device which, under the control of a caller, can be made to record a message or repeat a message previously recorded. The central office system which, for present identification may be termed the message bureau or center, is under the control of an operator in order that revenue can be collected upon the basis of time consumed in recording a message or having the message repeated. Other advantages of the invention will be apparent from the following detailed description wherein.

Fig. 1 is a diagrammatic illustration of the system as a whole; and

Figs. 2, 2^a and 2^b, when placed Fig. 2^a at the right of Fig. 2 and Fig. 2^b at the right of Fig. 2^a, show the circuit details of the system.

In accordance with the invention, a subscriber to the system will have an identifying number which can be published as are ordinary telephone numbers. Upon being connected with the message center, which is reached through incoming trunks 10, the caller will hear a dial tone whereupon he will dial the subscriber's number. Through line finders 11 and selectors 12 (indicated by an appropriately labeled box in Fig. 1), one of a group of connectors 13 will be picked up, i. e., the connector corresponding to the subscriber's number which was dialed. The board allotted to the final connectors 13 may have, for example, ten thousand positions and each subscriber's number can appear on several connectors to insure service even though one or more numbers in the same hundred block is in use.

Each connector 13 or group of connectors allocated to a given subscriber has a recorder selector 14 tied to it, the selectors in turn being connected to a series of recorders 15 which are multiplied across the selectors, the arrangement

enabling a relatively few recorders to serve a large number of connector positions (Fig. 1).

Referring now to Fig. 2, it will be observed that each selector 12 has tip, ring and sleeve brushes 16, 17 and 18 movable to different connector positions 13. The tip and ring brushes 16 and 17 are in the voice circuit and, when in service, will provide a through connection to the caller's telephone. The sleeve brush 18 is connected to a battery 19 which, in turn, is grounded as at 20. Each recorder selector 14 is provided with four contact brushes 21, 22, 23 and 24 movable as a unit to one or another of a plurality of different positions 25 at each of which there is connected a recorder mechanism 15.

The recorder selector brushes 21 and 22 are respectively in the tip and ring circuits and, as shown, are appropriately tied to the corresponding connector position 13. The brush 24 is connected to ground through a trip magnet 26 and a battery 27, the function of the trip magnet being described later on.

The remaining recorder selector brush 23 is connected to the armature 28 of a slow release relay 29, energized from a battery 30 grounded at 31. Also in the relay circuit, there is included a lead 32 and a pair of contacts 33 which, when closed, complete the relay circuit, one of the contacts being grounded at 34. Normally the slow release relay 29 is deenergized, its armature 28 engaging a back contact 35 grounded at 36. However, when the selector 12 reaches the connector position 13, dialed by the caller, its brush 18 establishes a circuit through a slow operating relay 37, thereby closing the contacts 33 and completing the circuit through the slow release relay 29. The slow operating relay 37 is energized from the battery 19 to which the selector brush 18 is connected, and its complete circuit includes a lead 38 connected at one end to the relay winding and at its other end to the recorder selector brush 23 when the recorder selector 14 is in its normal position. The circuit further includes a lead 39 connected at one end to the brush 23 and at its other end to the slow release relay armature 28 which as previously stated is normally grounded.

There is a slow operating relay 37 at each connector position 13 and it is designed to remain inactive until it has been energized for a period of 15 seconds. Thus, while each relay is momentarily energized during the sweep of the selector 12 to the dialed position, the relay 37 at the dialed position only will operate as the selector comes to rest in that position.

In addition to completing a circuit through the slow release relay 29, the closing of the contacts 33 also completes a circuit through a step magnet 40 whose winding is connected at one end to a battery 41, grounded at 42 and, at the other end, to the magnet's armature 43 which normally engages a contact 44 connected to the lead 32. As the step magnet 40 is energized, the recorder selector 14 is moved to the first recorder position 25 and, should the recorder there be idle, the recorder selector will come to rest, tying that recorder to the connector position of the dialed subscriber. However, if the first recorder position is in use, it will be grounded and the step magnet will continue to receive impulses until the recorder selector does arrive at an idle recorder position.

All impulses imparted to the step magnet 40 subsequent to the first, are delivered through a different circuit. When the slow release relay 29 is initially energized, the ground contact at 35 is broken, thereby deenergizing the slow operating relay 37 and allowing the contacts 33 to open. However, when the armature 28 of the slow release relay 29 is attracted thereby, it engages a top contact 45 so that the lead 39, which is connected to the recorder selector brush 23, will be in the circuit of both the slow release relay 29 and the step magnet 40. Because of its nature, the slow release relay will maintain the contact 45 closed despite the interruptions in current entailed by the stepping of the recorder selector from one position to another. And so long as the contact 45 does remain closed and the recorder selector encounters a grounded position, the step magnet 40 will receive a new impulse each time its armature 43 drops back to close the contact 44.

Of course, after the recorder selector has picked up an idle or ungrounded recorder, no further impulses will be imparted to the step magnet and shortly thereafter the slow release relay 29 will release its armature 28 allowing it again to engage the back contact 35 to ground that recorder position.

The recorder circuit includes two leads 46 and 47 connected in the tip and ring circuits and over which the caller's voice is transmitted to the recording apparatus and over which he hears the recorded message. The manner in which these leads are connected to the recorder, enabling them to perform their intended function, is described later on. Suffice it to say at the moment, as soon as the recorder selector has picked up an idle recorder, central office battery is supplied over the leads 46 and 47 to energize a slow release 48 and a pulsing relay 49, the windings of which are connected in series (Fig. 2a). The relay 48 acts to close four pairs of contacts 50, 51, 52 and 53 and remains active so long as the caller's receiver is off the hook. The contacts 50 are in a circuit which includes a step magnet 54 and which can be traced from a ground 55, through a battery 56, the contact 50, and through a lead 57 to the step magnet winding, and from the step magnet to a pair of contacts 58, one of which is grounded at 59. The contacts 58 are opened as soon as the pulsing relay is energized by the central office battery.

The step magnet 54 operates a function selector enabling the caller selectively to connect himself to the recording apparatus for recording or for receiving a recorded message. The function selector is so arranged that when the caller dials "1," he will be automatically connected for re-

cording a message, whereas when he dials "2," he will be automatically connected for receiving a message that has previously been recorded. To this end, the step magnet 54 has three positions, 60, 61 and 62, the position 60 being normal. As "1" is dialed, the supply of central office battery to the circuit through the slow release relay 48 and the pulsing relay 49 is momentarily suspended, permitting the contacts 53 to close and establish the circuit through the step magnet 54. This momentary interruption of the current, however, has no effect upon the slow release relay 48 which remains active. As the step magnet 54 is momentarily energized, an arm 63 with which it is provided is stepped to the first position 61. On the other hand, when the caller dials "2," the step magnet, in like manner, receives two current impulses, causing the arm 63 to step to position 62. It should be stated that the pulsing relay 49 is quick on make and break so that as soon as the current through it is established after each dialing pulse, the contacts 58 are immediately broken.

Depending upon whether the arm 63 has been stepped to the first position 61 or the second position 62, current from a battery 64, which is grounded at 65, will flow through the arm 63 to energize a relay 66 or 67, the windings of which have a common return to ground at 68. The relays 66 and 67 are slow operating so that the one selected by dialing "1" is not operated by the first of the two impulses resulting from dialing "2."

As the relay 66 is energized, a pair of contacts 69 and 70 operated thereby are closed, the contact 69 establishing a circuit through a relay 71 which prepares the recorder 15 to receive a message. The circuit through the relay 71 can be traced from a ground 72, through a battery 73 to the relay winding, and thence by way of a lead 74 to the contact 68 and ground at 75. On the other hand, as the relay 67 is energized, as when the caller dials "2," a pair of contacts 76 and 77 are closed thereby, the contact 76 establishing a circuit through a relay 78 which prepares the recorder 15 to repeat a message previously recorded. The circuit through the relay 78 can be traced from a ground 79, through a battery 80 to the relay winding and thence, by way of a lead 81 to the contact 76 and ground at 75.

The other contacts 70 and 77 closed by the selector relays 66 and 67, respectively, serve to energize a slow operating trip magnet 82 which, after said relays have performed their function, operates to restore the arm 63 of the step magnet 54 to its initial position 60. The circuit through the trip magnet can be traced from the ground 83 through the battery 84 to the trip magnet winding, then by way of a lead 85 to the contact 70 or 77, whichever is closed, and ground at 86.

The operation of the relay 71 performs four different functions. First, it closes a contact 87 which establishes a locking circuit for maintaining said relay active until the caller either hangs up the telephone receiver or dials "2" to reproduce the message. The locking circuit can be traced from the winding of the relay 71, through the battery 73 and a lead 88 to the contact 87, and from that contact through a lead 89 to a contact 90, which is normally closed when the relay 78 is inoperative. Thereafter the circuit proceeds through a lead 91 to the contacts 51 which, as will be recalled, were closed by the slow release relay 48 when the recorder was initially selected. The circuit returns from the contacts 51 back to the winding of the relay 71 through a lead 92. As stated, the circuit remains active

until it is broken at the contacts 51, when the caller hangs up, or at the contacts 90 should the caller dial "2."

Secondly, the relay 71 acts to connect the leads 46 and 47 of the voice circuit to the input of a recording amplifier 93 which amplifies the voice current preparatory to recording. This connection is established through a pair of contacts 94 and 95, which are closed upon the operation of the relay 71 and which connect the leads 46 and 47, respectively to a pair of leads 96 and 97, the latter in turn being connected to the input of the recording amplifier 93 through a suitable filter network 98 (see also Fig. 2b).

In the output of the recording amplifier, there is connected a magnetic recording device 99 which is operatively associated with a tape 100 of a character capable of being magnetized in accordance with the voice current.

Thirdly, the relay 71 acts to start a motor 101 in a direction to unwind the tape 100 off a drum 102 and onto a drum 103, the drum 102 being driven from the motor through a shaft 104 and in turn driving the drum 103 through a suitable belt 105. Since the tape 100 starts its forward movement simultaneously with the connection of the recorder with the caller's telephone, the system will be in readiness to record the message. The motor 101 is controlled in its forward movement from a motor control box 106 designed to operate the motor in a forward direction as a contact 107 operated by the relay 71 is closed. The motor forward control circuit includes a pair of leads 108 and 109 emerging from the motor control box and which terminate at said contact 107.

Fourthly, the relay 71 opens a normally closed contact 110 which is in a locking circuit associated with the relay 78 and which will be described presently.

Briefly then, when the caller dials "1" the circuit is conditioned to record the caller's message. Should he desire to have the message repeated back, that can be accomplished merely by dialing "2" without hanging up the receiver. Or, if a subsequent caller should desire to receive the message, that may be accomplished by calling the message center and upon receiving the dial tone, dialing the subscriber's number and then dialing "2." In the latter instance, that is where a subsequent caller desires to receive the message, it will not be necessary for the recorder selector 14, allotted to the subscriber's connector, to hunt the recorder on which the message has been impressed since the recorder remains connected to the subscriber's recorder selector for a given period determined in a manner pointed out later on.

As the number "2" is dialed either by the caller who wishes his message repeated back or by a subsequent caller desiring to obtain the message, the relay 78 is energized by the function selector in the manner previously described. The relay 78 performs five functions. First, it acts to close contacts 111 to complete a locking circuit similar to that of the relay 71. The circuit may be traced from the winding of the relay 78, through the battery 80, to the contacts 111, then by way of a lead 112 to the contacts 110 which are normally closed when the relay 71 is deenergized. From the latter contacts, the circuit follows a lead 113 connected through the contacts 52 with a lead 114 passing back to the relay winding. If the condition is one where

the caller is having the message he gave repeated back, the contacts 52 will, of course, have been closed by the operation of the slow release relay 48 at the time the recorder was initially connected to the recorder selector. In the case of a subsequent caller, however, the contacts 52 will be closed as soon as the caller's line is coupled to the subscriber's connector since at that time, the central office battery will be impressed upon the said relay 48.

Secondly, the relay 78 connects the voice circuit, i. e., the leads 46 and 47, to the output of a reproducing amplifier 115 through a suitable filter network 116 and a pair of leads 117, 118 terminating in contacts 119 and 120 which are closed when the relay is energized. The input circuit of the amplifier is connected to a magnetic pickup device 121 operatively associated with the tape 100 on which the message is recorded.

Thirdly, the relay 78 initiates the operation of the motor 101 in the reverse direction so as to wind the tape 100 back upon the drum 102 to its initial position in order that the message can be repeated from the beginning. The relay 78 accomplishes this function by closing a pair of contacts 122 which, through an appropriate circuit in the motor control box 106, reverses the motor's field connections. The contacts 123 are connected to the motor control box through one direct lead 123 and a second lead 124 which includes a pair of contacts 125, the latter being normally closed so that when the contacts 122 are closed by the operation of the relay 78 the motor will start immediately to reverse.

The shaft 104 of the motor 101 is provided with a threaded sleeve 126 located initially at the left end of the shaft but which is so guided that as the motor turns in a forward direction, the sleeve will move toward the right a distance proportional to the amount of tape unwound during the initial recording of the message. When the motor starts to reverse, the sleeve 126 moves toward the left back along the shaft to its initial position at which time, all of the tape involved in previous message recording will be wound up upon the drum 102. When the sleeve 126 reaches its normal position, it closes a pair of contacts 127 thereby completing a circuit from ground at 128 through the winding of a relay 129 to a battery 130 grounded at 131. As the relay 129 is thus energized, it opens the contacts 125 in the motor reversing circuit and simultaneously closes two other pairs of contacts 132 and 133. The contacts 132 establish the motor forward circuit while the contacts 133 establish a locking circuit for the relay 129. This locking circuit, in addition to the battery 130, the relay winding and the contacts 133 just alluded to, includes also a pair of contacts 134, the closing of which is another function performed by the relay 78. The locking circuit maintains the relay 129 active, thus insuring that the motor will continue to move the tape forward until the caller has heard the full message. The locking circuit is broken and the parts restored to their normal positions when the relay 78 is deenergized. That condition will occur when the caller hangs up or when he dials "1," should he also wish to have a message recorded. Should a caller dial "2" to receive a message and then desire to have the message repeated, it would be necessary for him first to dial "1" so as to break the locking circuit through the relay 78 and then dial "2," thus to insure that the tape will be returned to its initial

position before the recorder starts to repeat the message a second time. It is suggested that the instructions for use provide that the caller dial "11" for recording and "12" for receiving the message, thereby eliminating any possibility of confusion.

From what has been said, it is apparent that the present system will enable a subscriber to call the message center and leave a message should he desire to absent himself from the place where he usually can be reached and will also enable another person to call the message center and receive the subscriber's message. Furthermore, any person desiring to transmit a message to the subscriber can call the subscriber's number and leave a message which he subsequently can obtain.

Also in accordance with the invention, it is proposed that the recorder remain tied to the subscriber's line for a definite period of time after the connection therewith has been made. At the end of that period, the recorder is automatically disconnected from the subscriber's connector and the message erased, thereby leaving the recorder idle and in condition to be connected to another subscriber's line. For this purpose, there is provided a circuit which includes a clock mechanism 135 operated from a 60 cycle current source 136, the mechanism being designed to have a cyclic period of, say, twenty-four hours if that is the period decided upon to maintain the recorder connected to the subscriber's line. When the recorder is initially connected at the subscriber's position, the fourth pair of contacts 53 closed by the operation of the slow release relay 48 complete a circuit from ground at 131 through a relay 138, a battery 139 and back to ground at 140. As the relay 138 is energized, it closes two pairs of contacts 141 and 142, which respectively establish a circuit starting the clock mechanism and a locking circuit for the relay 138, the latter circuit including the battery 139 and a pair of contacts 144 which are normally closed. The clock motor 135 is provided with a cam shaft 145 upon which there are mounted three cams 146, 147 and 148, and which is arranged to rotate once during each cyclic period. As the cyclic period nears its end, the cam 146, which is suitably formed for the purpose, acts to separate the contacts 144, thereby breaking the locking circuit and deenergizing the relay 138. Thereupon the contacts 141 and 142 are restored to their original open positions with the result that the circuit through the clock mechanism is broken.

Simultaneously, the cam 147 acts to close a pair of contacts 149 to establish a circuit through the trip magnet 26 associated with the recorder selector. This circuit includes the brush 24 of the recorder selector and a lead 150 connecting the contacts 149, one of which is grounded to the recorder position at which the selector is located. As the magnet 26 is energized, the recorder selector will be restored to its normal position, thereby rendering the recorder idle.

Also at the end of the cyclic period, the cam 148 acts to close two pairs of contacts 151 and 152. The closing of the contacts 151 establishes a circuit through a battery 153 and a magnetic erasing device 154 associated with the recording tape 100 and whose function it is to erase the previously recorded message from the tape. The closing of the contacts 152 which are in a circuit leading to the motor control box, acts to reverse the motor 101 to cause that portion of the tape upon which the message was recorded to pass

beneath the erasing device 154 and permit the latter to perform its intended function. Suitable means (not shown) are provided to recycle the clock mechanism and place it in condition to commence its timing action when the recorder is again selected.

There is one situation that might give trouble were corrective measures not provided. Thus, in the absence of such measures, if a person calling to receive a message hung up the receiver before the full message had been repeated, the message of a person subsequently calling to record would overlap the unfinished portion of the original message. To obviate that difficulty, there is provided a voice operated relay 155 connected in the output circuit of the reproducing amplifier 115 and which will act to maintain closed a pair of contacts 156 in the motor forward control circuit so long as there is any voice reproduction. Thus, even though the telephone receiver is hung up before the message is completed, the tape will continue to move forward until all of the used portion has traveled past the pickup device, with the result that a fresh portion of the tape will be presented to the recording device 99 should a person subsequently call to record a new message.

While no details of the motor control box have been shown, a suitable circuit capable of performing the functions attributed to it will readily suggest itself to one skilled in the art. Thus, by way of example, connections in the nature of a double pole, double throw switch can be utilized for reversing the field current, the switch poles being appropriately connected through elements actuated by relays connected respectively in the circuits which include the contacts heretofore designated as the motor forward control circuit and the motor reverse control circuit.

In the accompanying drawings, the invention has been shown merely by way of example and in preferred form, but obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. In a telephone system for recording and repeating messages, the combination of a recording and repeating device, circuit connections under the control of a caller for selectively conditioning said device for recording a message or for repeating a recorded message, and means for automatically erasing the message at the expiration of a predetermined period.

2. In a telephone system for recording and repeating messages, a central office provided with a plurality of positions individual to different subscribers and connectible each to a recording and repeating device at said central office, trunk lines enabling a caller to be selectively connected to any desired one of said positions, and means under the control of the caller and operable while he is connected to a recorder-repeater device for selectively conditioning said recorder-repeater device for recording a message or for repeating a recorded message as desired.

3. In a telephone system for recording and repeating messages, a central office provided with a plurality of positions individual to different subscribers, trunk lines enabling a caller to be selectively connected to any desired one of said

positions, a plurality of recorder-repeater devices at said office, a recorder-repeater selector associated with each of said positions and connectible to the recorder-repeater devices, said recorder-repeater selector acting automatically when a caller is connected at its position to select an idle recorder-repeater device, and means under the control of the caller for selectively conditioning said device for recording a message or for repeating a recorded message.

4. A telephone system according to claim 3, wherein means are provided for maintaining the selected recorder-repeater device locked to the subscriber's position after the caller has been disconnected to enable a subsequent caller connected to said subscriber's position to be connected to the same recorder-repeater device.

5. A telephone system according to claim 3, wherein means are provided for locking the selected recorder-repeater device to the subscriber's position for a predetermined period.

6. A telephone system according to claim 3, wherein means are provided for locking the selected recorder-repeater device to the subscriber's position, and means for automatically disconnecting the recorder-repeater device from said subscriber's position at the expiration of a predetermined period.

7. A telephone system according to claim 3, wherein means are provided for maintaining the selected recorder-repeater device locked to the subscriber's position after the caller has been disconnected to enable a subsequent caller connected to said subscriber's position to be connected to the same recorder-repeater device, and means for subsequently erasing a message from the recorder-repeater device.

8. A telephone system according to claim 3, wherein means are provided for locking the selected recorder-repeater device to the subscriber's 40 position, and means acting automatically at the

expiration of a predetermined period to effect the disconnection of the recorder-repeater device from said subscriber's position and the erasure of messages that have been recorded.

9. A telephone system according to claim 3, wherein means are provided for locking the selected recorder-repeater device to the subscriber's position, means for disconnecting said device from the subscriber's position, means for erasing messages that have been recorded, and a timing control whose operation is initiated upon the connection of the recorder-repeater at the subscriber's position and which acts after a predetermined period automatically to operate said disconnecting means and said message erasing means.

10. In a telephone system for recording and repeating messages, a recorder-repeater device equipped with means enabling a caller using the system selectively to condition the device for recording or repeating messages, said device including an element on which the message is recorded and from which the message is repeated, means operable upon conditioning the device for recording to actuate said element in one direction, means operable upon conditioning the device for repeating to actuate said element in the reverse direction, and means acting upon the arrival of the element in its original position automatically to initiate its movement in the original direction to enable the recorded message to be repeated.

11. A telephone system according to claim 10, wherein the recorder-repeater device is provided further with means to insure the continued movement of the recording element to the end of the recorded message in the event the caller discontinues his use of the device prior to the termination of said message.

I. LAWRENCE LESAVOY.
